(57) CLAIM

The ornamental design for “a toothbrush holder”, as shown.

DESCRIPTION

FIG. 1 is a Front Perspective View showing my new design;
FIG. 2 is a Rear Perspective View thereof;

FIG. 3 is a Front View thereof;

FIG. 4 is a Back View thereof;

FIG. 5 is a Bottom View thereof;

FIG. 6 is a Left View thereof;

FIG. 7 is a Right View thereof; and,

FIG. 8 is an Isometric View of Holder With Brush.

The broken-line disclosure of the toothbrush in the views is
for illustrative purposes only and forms no part of the
claimed design.
